UNITED STATES PATENT OFFICE.

MAX TONK, OF CHICAGO, ILLINOIS.

DESIGN FOR A PIANO-STOOL.

SPECIFICATION forming part of Design No. 21,695, dated July 5, 1892.

Application filed March 26, 1892. Serial No. 426,606. Term of patent 3½ years.

To all whom it may concern:

Be it known that I, MAX TONK, a citizen of the United States, residing at Chicago, Illinois, have invented a certain new and useful 5 Design for Piano-Stools, of which the following is a specification.

My invention relates to a new and original design for piano-stools.

The leading feature of the design consists 10 in thickly-set curved relief-forms narrow at their bases and rounded toward their extremities, the extremity of one overlapping the base of the next succeeding one, said forms being arranged in bands and applied to the 15 legs of the pedestal and the frame of the seat.

My design is shown in the accompanying drawing, which is a perspective view of a piano-stool.

In said drawing, A represents the seat and B the pedestal. The seat has upon its frame 20 and the pedestal has upon the sides of its legs surface ornamentation in the form of bands C, composed of the relief-forms c, arranged in parallel lines, so as to form two rows of said relief-forms making up each band. These 25 relief-forms c have narrow bases and rounded extremities and are thickly set, so that the extremity of one overlies the base of the other.

I claim—

The design for piano-stools herein shown 30 and described.

MAX TONK.
